US0D1081269S

(12) **United States Design Patent** (10) Patent No.: **US D1,081,269 S**
(45) Date of Patent: ** Jul. 1, 2025

(54) **CONTAINER**

(71) Applicant: **Closure Systems International Inc.**,
Indianapolis, IN (US)

(72) Inventor: **Aravind Murali**, Zionsville, IN (US)

(73) Assignee: **CLOSURE SYSTEMS
INTERNATIONAL INC.**, Indianapolis,
IN (US)

(**) Term: **15 Years**

(21) Appl. No.: **29/776,481**

(22) Filed: **Mar. 30, 2021**

(51) LOC (15) Cl. **07-01**

(52) U.S. Cl.

USPC **D7/532**; D7/602
